223,291

COMBINED DISPLAY AND BOX DISPENSING UNIT

Alexander N. Schoenfeld, Roslyn Heights, N.Y., assignor
to Trans World Display Corporation

Filed Aug. 18, 1970, Ser. No. 24,562

Term of patent 14 years

Int. Cl. D9—99

U.S. Cl. D52—2

FIG. 2

FIG. 3

FIG. 1

FIG.5

FIG.6

FIG.4

FIG. 7

FIG. 1 is a left side elevational view showing my new design for a combined display and box dispensing unit;

FIG. 2 is a front elevational view;

FIG. 3 is a top view;

FIG. 4 is a right side elevational view;

FIG. 5 is a rear view;

FIG. 6 is a bottom view; and

FIG. 7 is a front perspective view, the front of the unit being partially open.

I claim:

The ornamental design for a combined display and box dispensing unit, substantially as shown.
